DESIGN FOR A VENDING OR SALES BOOTH

Application filed July 27, 1931. Serial No. 40,697. Term of patent 14 years.

To all whom it may concern:

Be it known that I, FRED HEBEL, a citizen of the United States, residing at Chicago, in the county of Cook and State of Illinois, have invented a new, original, and ornamental design for Vending or Sales Booth, of which the following is a specification, reference being had to the accompanying drawings, forming a part thereof, in which—

Figure 1 is a front elevation and Figure 2 is a perspective view of a vending or sales booth showing my new design.

The opposite side of the design is usually plain although obviously the illustrated design may be repeated on the opposite side if desired.

I claim—

The ornamental design for a vending or sales booth, substantially as shown and described.

FRED HEBEL.
